UNITED STATES PATENT OFFICE

ELMER C. PATZKOWSKI, OF COMPTON, CALIFORNIA, ASSIGNOR TO ELMER C. PATZKOWSKI, EDGAR TRUETT AND HERBERT OWSLEY, TRUSTEES

DESIGN FOR AN AEROPLANE

Application filed December 29, 1930. Serial No. 38,136. Term of patent 7 years.

To all whom it may concern:

Be it known that I, ELMER C. PATZKOWSKI, a citizen of the United States, residing at Compton, in the county of Los Angeles and State of California, have invented a new, original, and ornamental Design for an Aeroplane, of which the following is a specification, reference being had to the accompanying drawing forming part thereof.

Fig. 1 is a plan view of an aeroplane showing my new design.

Fig. 2 is an elevation taken in the direction of the arrow 2 of Figure 1.

Fig. 3 is a side elevation taken in the direction of the arrow 3 of Figure 1.

I claim:

The ornamental design for an aeroplane, as shown.

ELMER C. PATZKOWSKI.
